UNITED STATES PATENT OFFICE.

ALFRED A. HULL, OF KNOXVILLE, TENNESSEE.

FLUE-CLEANER.

SPECIFICATION forming part of Letters Patent No. 691,057, dated January 14, 1902.

Application filed April 6, 1901. Serial No. 54,849. (No model.)

To all whom it may concern:

Be it known that I, ALFRED A. HULL, a resident of Knoxville, Tennessee, have invented a new and useful Improvement in Flue-Cleaners, which invention is fully set forth in the following specification.

My present improvements relate to steam-boiler-flue cleaners. The invention is an improvement upon Letters Patent No. 600,286, granted to me March 8, 1898. I have found that in flue-cleaners constructed in accordance with the drawings of that patent there was a tendency of the transverse scraper-blades to jam within the flue, generally near the end of the flue, owing to the absence of proper guiding instrumentalities. There was danger, also, of the retaining means for the nuts or sleeves which secure the adjustable scraper-blades getting loose and dropping off in the flue. Other improved specific features have also been adopted which will be herein-after referred to.

My invention consists in the following construction and combination of parts, the details of which will be first fully described and the patentable features then set forth and claimed.

Figure 1 represents a plan view of a flue-cleaner embodying my invention. Fig. 2 is a similar view, partly in central longitudinal section. Fig. 3 is a cross-section showing the longitudinal fingers in dotted lines. Fig. 4 is a cross-section of the flue-cleaner in the neighborhood of the scraper-blades.

In the drawings, 1 represents a rod having opposite threaded ends to which the operating parts of my flue-cleaner are attached.

2 represents radial pairs of lugs.

3 represents a series of longitudinally-disposed fingers pivoted at 4 in the lugs 2, so as to permit limited movement laterally as well as radially of the rod 1.

5 represents leaf-springs, one for each finger 3, acting constantly to throw the free ends of the fingers outwardly. These springs are bent at their lower ends to enter a depression 6 in the fingers and concaved at their upper contacting-surfaces 7 to embrace a corresponding convexity on the fingers 3. This construction dispenses with the pivoting of the

springs and allows of their easy assemblage in proper position.

8 represents two pairs of collars rigidly formed on the rod 1, preferably cored and shaped as shown, in order to combine strength and lightness. These collars 8 are slotted lengthwise of the rod 1 to permit the adjustable play of fingers 3. The collars are also slotted transversely of the rod to accommodate a set of circumferential scraper-blades 9 in their adjusting movements.

Scraper-blades 9 are preferably segment-shaped and disposed in parallel adjacent planes. The ends of the blade-segments overlap, forming practically a continuous peripheral cutting or scraping edge.

The free ends of fingers 3 are slotted at 10, and the bodies of the fingers are shaped opposite the slots as shown at 11, the ends of the fingers terminating in converging or curved tips adapted to be embraced by a conical nut 13 for adjusting the same. The scraper segment-blades 9 have openings therein through which the free ends of the fingers are inserted, and the segments are slipped down over 75 and into the slots 10 and over the inwardly-projecting portions 11. In this position the blades may be held on the fingers when the latter are without the slot between the collars 8.

The upper threaded end of rod 1 has, preferably, a spline 14, within which a key or detent 15 on the sleeve 16 takes to prevent the latter turning in its vertical movement. The conical lock-nut 17 locks the nut 13 in place. 85 A key-seat and key 18 prevent the inadvertent displacement and loss of any of the parts.

The peculiar conformation of the outer edges of the fingers 3 in the region of the scraper-blades is material. The edges of the 90 fingers at that point are practically flush with the scraper-blades and gradually recede therefrom inwardly. As a result it is impossible by careless handling to insert the tool out of line with the tube in such manner as to jam 95 the tool in the tube. This was a serious objection in the tool described in my previous patent referred to herein.

The setting up of the nut 13 causes the fingers and blades to approach each other. The 100

opposite movement permits the springs 5 to exert a contrary movement. In this manner the blades are adjustably set in and out.

What I claim is—

- 5 1. In a flue-cleaner, the combination of a rod, fingers carrying scrapers pivoted to the rod having a recess and a convexity, a spring for each finger having a projection taking into said recess upon one side of the pivotal points of the fingers, and a concavity embracing said convexity upon the opposite side of said pivotal points, collars for holding the scraper-blades, and means for adjustably setting the fingers.
- 10 2. In a flue-cleaner, the combination of a rod, a pair of segment-shaped collars rigidly

secured to said rod, said collars having radial slots therein and cored-out portions between said slots, fingers pivoted to the rod carrying scrapers within the collars, an adjusting-nut for the fingers, a sleeve beyond the nut, means for preventing the rotation of the sleeve upon the rod, a lock-nut beyond the sleeve and means for securing the lock-nut from becoming displaced.

In testimony whereof I have signed this specification in the presence of two subscribing witnesses.

ALFRED A. HULL.
